DESIGN FOR A NET FABRIC OR SIMILAR ARTICLE

Gustave Bloch, New York, N. Y.

Application February 11, 1937, Serial No. 67,580

Term of patent 3½ years

To all whom it may concern:

Be it known that I, Gustave Bloch, a citizen of the United States of America, residing in city of New York, county of New York, and State of New York, have invented a new, original, and ornamental Design for a Net Fabric or Similar Article, of which the following is a specification, reference being had to the accompanying drawing, forming part thereof.

The figure of the drawing is a plan view of a net fabric or similar article showing my new design.

The design unit is contained between the dot and dash lines, which unit is repeated in regular succession, as indicated by the extensions beyond the unit boundaries.

I claim:

The ornamental design for a net fabric or similar article substantially as shown and described.

GUSTAVE BLOCH.
